[57] CLAIM

The ornamental design for a combined container and sealing ring, as shown and described.

DESCRIPTION

FIG. 1 is a side elevational view of a combined container and sealing ring showing my new design;

FIG. 2 is a top plan view of the sealing ring;

FIG. 3 is a side elevational view thereof;

FIG. 4 is a bottom plan view thereof;

FIG. 5 is a top plan view of the container;

FIG. 6 is a side elevational view thereof;

FIG. 7 is a bottom plan view thereof;

FIG. 8 is an enlarged, side, fragmentary elevational view, partly in section, of the sealing ring taken along line 8—8 of FIG. 2; and

FIG. 9 is an enlarged, fragmentary side elevational view, partly in section, of the container taken on the line 9—9 of FIG. 5.

FIG. 1.

FIG. 2.

FIG. 3.

FIG. 4.

FIG. 5.

FIG. 6.

FIG. 7.

FIG. 8.

FIG. 9.
